(57)

CLAIMThe ornamental design for an aerosol generating device, as
shown and described.**DESCRIPTION**

1. Aerosol generating device

Design 1: an aerosol generating device; fig. 1.1 perspective
view; fig 1.2 another perspective view; fig 1.3 front view; fig
(Continued)1.4 rear view; fig 1.5 top view; fig 1.6 bottom view; fig 1.7 right-side view; fig 1.8 left side view.

1 Claim, 8 Drawing Sheets
